UNITED STATES PATENT OFFICE.

BALDWIN H. FOSTER, OF UTICA, NEW YORK, ASSIGNOR OF ONE-HALF TO FRED W. SIMON, OF UTICA, NEW YORK.

PICTURE-PROJECTING MACHINE.

1,264,869.

Specification of Letters Patent. Patented Apr. 30, 1918.

Application filed April 5, 1917. Serial No. 159,946.

To all whom it may concern:

Be it known that I, BALDWIN H. FOSTER, a citizen of the United States of America, residing at Utica, in the county of Oneida and 5 State of New York, have invented certain new and useful Improvements in Picture-Projecting Machines, of which the following is a specification.

This invention relates to picture project- 10 ing machines and has for its principal object the production of simple and efficient means for stopping a motion picture machine and cutting off the electric arc provided the film is broken. 15 Another object of this invention is the production of a picture projecting machine attachment which is provided with a plunger so arranged as to bear upon the film whereby in case the film is accidentally 20 broken the plunger will move so as to permit a circuit closing means to operate for starting a motor which will in turn throw a switch so as to stop the motion picture machine, cut off the electric arc, and at the 25 same time stop the first-mentioned motor.

Another object of this invention is the production of an attachment for picture projecting machines wherein a trip arm is provided which is so arranged as to be automatically tripped provided the film is broken 30 so as to close the circuit for stopping the motion picture machine and cutting off the electric arc, thereby preventing fires ordinarily incurred due to the breaking of the 35 film.

With these and other objects in view, this invention consists of certain novel combinations, constructions and arrangements of parts as will be hereinafter fully described 40 and claimed.

In the accompanying drawings:

Figure 1 is a side elevation of the attachment for a picture projecting machine.

Fig. 2 is a central vertical section through 45 the circuit closing mechanism.

Fig. 3 is a section taken on line 3—3 of Fig. 1 looking in the direction of the arrows.

Fig. 4 is a horizontal section through the housing for the circuit closing means, showing the circuit closing means in top plan. 50

Fig. 5 is a section taken on line 5—5 of Fig. 2, looking in the direction of the arrows.

Fig. 6 is a detail perspective view of the plunger housing.

Fig. 7 is a section taken on line 7—7 of

Fig. 2, looking in the direction of the arrows.

Fig. 8 is a section taken on line 8—8 of Fig. 2, looking in the direction of the arrows.

Fig. 9 is a detail perspective view of the 60 trip arm and trip rod.

Fig. 10 is a detail perspective view of the plunger.

Fig. 11 is a top plan view of the switch throwing motor. 65

Fig. 12 is a vertical section taken on line 12—12 of Fig. 1, looking in the direction of the arrows.

Fig. 13 is a plan view of the switch, showing the disk used for throwing the switch 70 in section.

Referring to the accompanying drawings by numerals it will be seen that the attachment is adapted to be mounted upon the supporting table 1 having the usual supporting stands 2. It is, of course, obvious that this device is intended to be used with any form of a picture projecting machine for it will readily stop the action of the machine and cut off the arc light, provided the 75 film is accidentally broken, irrespective of the specific construction of the picture projecting machine.

The box 3 is mounted upon the table 1 while the reels 4 are rotatably mounted in 80 any desired manner adjacent the ends of the box 3. The film 5 passes around the idlers 6 in passing through the box 3 from one reel to the other, as shown clearly in Fig. 2.

The housing 7 is permanently carried 90 upon the table 1 and this housing 7 is provided with a base 8, sides 9, ends 10 and top 11. It is intended to form this housing 7 of fiber or some similar suitable material of a non-conducting nature so as to positively prevent any short circuits when the device is in operation. This housing 7 is carried upon the table 1 as above set forth so as to have one of its ends 10 abutting against the box 3, as shown in Figs. 100 1, 2 and 4.

The plunger tube 12 is carried upon the base 8 of the housing 7 and projects through one end of the housing 7 into the box 3, as shown clearly in Figs. 2 and 4. The plunger 105 tube 12 is rectangular in cross section and, therefore, the plunger 13 which is reciprocally mounted within the plunger tube 12 will be positively held against rotation. This plunger 13 has L-shaped arms 14 110

formed upon one end thereof, upon which the roller 15 is rotatably mounted. This plunger 13 is normally urged in one direction since the coil spring 16 is positioned thereon and this coil spring 16 bears at one end against the plunger tube 12 and at its opposite end against the arms 14. The roller 15 normally bears against the film 5 when the picture projecting machine is in 10 operation and, therefore, the plunger 13 will be held in a set position against the tension of the coil spring 16. This plunger 13 is considerably longer than the tube 12 and has a beveled inner end as indicated 15 at 17.

A guide rod 18 is carried by the base 8 and top 11 of the housing 7 and this guide rod 18 passes through the opening 19 formed in the trip arm 20. A coil spring 21 is 20 secured at one end to the trip arm 20 and at its opposite end to the base 8 so as to normally urge the trip arm 20 downwardly. This trip arm 20 is normally retained in an elevated set position, however, by the trip 25 rod 22. The trip rod 22 bears at its upper end against the trip arm 20 while the lower end of this trip rod 22 rests upon the plunger 13. If, however, the film 5 is broken, the tension of the spring 16 will 30 move the plunger 13 to a greater distance into the box 3 and, therefore, the plunger will move out from under the trip rod 22. As soon as this action takes place, it is obvious the trip rod 22 will fall and therefore 35 the trip arm 20 will be without support. Owing to the weight of the trip arm, together with the urging of the coil spring 21, the trip arm will move downwardly, being guided by the rod 18.

40 A contact point 23 is carried by this trip arm 20 while a contact point 24 is carried by the base 8 of the housing 7. These contact points 23 and 24 are in alinement with each other under normal conditions and, 45 therefore, when the trip arm 20 moves downwardly, the contact point 23 will engage the contact point 24 and thus close the circuit.

A block 25 may be carried in any desired 50 position adjacent the attachment, and a motor 26 is fixedly mounted upon this block 25. The shaft 27 extends from the motor 26 and has a gear 28 keyed thereto, which gear 28 meshes with the gear 29 which in 55 turn has a shaft 30 keyed thereon. A three-fold switch 31 is also carried upon the block 25 and has the pins 32 extending therefrom. The disk 33 is keyed upon the shaft 30 as shown at 34 and, therefore, it will be 60 seen that as rotary motion is imparted to the shaft 30, the disk 33 will also be rotated. A transverse pin 35 is carried by the disk 33 adjacent its periphery so that when the disk 33 is rotated sufficiently, the pin 35 65 will be swung into engagement with the

pins 32 on the switch 31, thereby swinging the switch 31 so as to break the various circuits to be hereinafter set forth.

A wire 36 is connected to the point 24 and to the motor 26. A wire 37 leads from the motor 26 and is connected to one pole of the switch 31, while a wire 38 leads from the pole of the switch just mentioned to a suitable source of supply. A return wire 39 is connected to the point 23 on the trip arm 20 and this wire 39 is provided with a hand switch 40. This wire 39 is also intended to be connected to the source of supply to which the wire 38 is connected so as to form a complete circuit when the points 30 23 and 24 engage each other.

A motor 41 is supported in any suitable manner upon the table 1 for the purpose of operating the picture projecting machine which is to be used in connection with the 85 present invention. The wire 42 connected to the motor 41 is in turn connected to a suitable source of supply, while the wire 43 is connected to the middle pole of the switch 31 as shown in Fig. 1 and from this middle pole there extends a wire 44 to be connected to the same source of supply as the wire 42. Therefore, it will be seen that when the switch 31 is in a closed position the circuit is formed so as to cause an electric 95 current to pass over wire 42 to the motor 41 for running this motor, while the current will return over wire 43, the middle pole of the switch 31 to the wire 44. The electric arc 45 is also supported upon one 100 of the standards 2, if so desired, and has the wire 46 extending to a source of electrical supply. A wire 47 passes to one of the outer poles of the switch 31 and from this outer pole last mentioned there extends a 105 wire 48 extending to the same source of supply as the wire 46. Therefore, when the switch is in a closed position an electric current will pass over the wire 46 to the electric arc 45, while the current will return over the wire 47, one of the outer poles of the switch 31 to the wire 48.

When this device is in operation it will be set up as shown in Figs. 1 and 2. At this time the switch 31 will be closed so as to 115 provide circuits for the electric arc 45 and the motor 41. If the film 5 is accidentally broken, the plunger 13 will move so as to permit the trip arm 20 to move so as to cause the points 23 and 24 to engage each 120 other, as herein before set forth. The engagement of these contact points 23 and 24 closes the circuit over wires 36, 37, 38 and 39 for starting the motor 26. The action of this motor will rotate the gears 28 125 and 29 and the disk 33 until the pin 35 of the disk will engage the pins 32 of the switch, thus operating the switch for breaking the circuits of the electric arc and the motor used for running the picture projecting ma- 130

chine, as well as the last-mentioned circuit which operates the motor 26. As all currents at this time are broken, it is obvious that the arc light will be cut off and the machine will stop, thus positively preventing the accidental fires caused when films are broken or by the improper operation of the machine.

From the foregoing description it will be seen that a very simple and efficient means has been provided for automatically stopping the picture projecting machine and cutting off the electric arc provided the film is broken, while the means for performing this operation is normally retained in a set position for carrying out this function at any time provided the film is broken as above set forth.

Having thus described my invention what is claimed is:

1. In a device of the class described, the combination of a switch, an auxiliary motor, a gear keyed to said auxiliary motor, a secondary gear meshing with said first-mentioned gear, a shaft keyed to said last-mentioned gear, a disk keyed upon said shaft, a pin carried by said disk, an electric arc circuit connected to said switch, a picture projecting machine motor circuit connected to said switch, and means for automatically closing a circuit for operating said auxiliary motor provided a film becomes broken whereby said disk will be rotated so as to cause the pin thereof to engage the pins of said switch for operating said switch for breaking all of said circuits.

2. In a device of the class described, the combination of a housing, a plunger tube carried by said housing, a plunger reciprocally mounted within said tube, means for normally urging said plunger in one direction, a guide rod carried within said housing, a trip arm slidably mounted upon said

guide rod, a trip rod supported upon said plunger and bearing against said trip arm for supporting said trip arm, a contact point carried by said trip arm, a contact point carried by said housing, means for forming an electric circuit connected to said contact points, said plunger being adapted to move in one direction provided a film is broken whereby said trip rod will be permitted to fall thus permitting the trip arm to move downwardly for causing said contact points to engage each other for closing a circuit.

3. In a device of the class described, the combination of an auxiliary motor, a switch, means connecting said motor to said switch for causing said switch to be operated by said motor, a main motor circuit connected to said switch, an electric arc circuit connected to said switch, a housing, a plunger tube carried by said housing, a plunger reciprocally mounted within said tube, a roller carried by one end of said plunger and normally riding upon a film, a coil spring engaging said plunger for normally urging the same in one direction, a trip arm carried within said housing, means for forming a guide for said trip arm, a trip rod carried upon said plunger and bearing upon said trip arm for normally retaining said trip arm in a set position, means connected to said auxiliary motor and extending into said housing for forming an electric circuit provided said plunger moves upon the breaking of a film and the descending of the trip arm whereby said switch will be operated for the breaking of all of said circuits.

In testimony whereof I affix my signature in the presence of two witnesses.

BALDWIN H. FOSTER.
